UNITED STATES PATENT OFFICE.

WILLIAM F. PERSONS, OF LAKEWOOD, OHIO, ASSIGNOR TO THE GUIDE MOTOR LAMP MANUFACTURING COMPANY, OF CLEVELAND, OHIO, A CORPORATION OF OHIO.

AUTOMOBILE-LAMP.

1,214,583.

Specification of Letters Patent. Patented Feb. 6, 1917.

Application filed August 5, 1916. Serial No. 113,217.

To all whom it may concern:

Be it known that I, WILLIAM F. PERSONS, a citizen of the United States, residing at Lakewood, in the county of Cuyahoga and 5 State of Ohio, have invented a certain new and useful Improvement in Automobile-Lamps, of which the following is a full, clear, and exact description, reference being had to the accompanying drawings.

10 This invention relates generally to automobile lamps and it has for its object to provide certain improvements to the automobile lamp now in common use whereby the intense glare can be eliminated when 15 desired and a sufficient amount of light thrown directly upon the road at the proper distance in advance of the automobile.

Another object of the invention is to provide the improvements in such form, and 20 arranged in such manner as will not interfere with the main or general searchlight functions of the lamp when it is desired to employ all of the light rays.

With these objects in view, the invention 25 consists in the arrangement of a supplemental reflector within the confines of the main reflector, preferably adjacent one edge thereof and at a slight angle to the axis of the main reflector so that by cutting out the 30 main source of light from the main reflector and cutting in the supplemental source of light within the supplemental reflector a smaller light will be thrown upon the road the proper distance in advance of the automobile.

35 The invention consists also in certain details of construction and arrangement hereinafter fully described and pointed out in the claims.

40 In the drawings forming a part of this specification Figure 1 is a longitudinal sectional view of an automobile lamp embodying my invention; Fig. 2 is a front view of the same; and Fig. 3 is a diagrammatic 45 view illustrating the lines of reflection of the light rays from both the main and supplemental reflectors.

50 Inasmuch as my invention can be applied to any and all of the well known types of electric automobile lamps I have shown the same applied to one in which A indicates the outer shell or body of the lamp, and B the reflector arranged therein, this reflector being preferably parabolic and having a

central opening in which is arranged the 55 socket for the incandescent light C. This incandescent lamp may be adjustable or stationary as preferred. The lamp is provided with the usual glazed front D which may be secured in any suitable manner such as a 60 clamping ring E.

F indicates a supplemental reflector which in diameter is slightly less than one half the diameter of the main reflector B, and this reflector F is arranged within the 65 confines of the main reflector adjacent the lower edge thereof and is preferably inclined at a slight angle to the axis of the main reflector so that instead of reflecting the light rays directly forward, said rays 70 will be directed downwardly so as to strike the road in advance of the car. The supplemental reflector F is connected to the main reflector by means of a sleeve G in which is located the socket of the supplemental lamp H. If desired the lower edge 75 of the supplemental reflector can be secured to the main reflector by means of screws or rivets I and it will be noted that the lower edge of the supplemental reflector 80 is set slightly back from the lower edge of the main reflector while the upper edge K is on a line with the outer edge of the main reflector. It will also be noted that this upper edge K approximates the center of 85 the main reflector and its source of light. Both the inner and the outer surface of the supplemental reflector H are polished to provide reflecting surfaces.

When the lamp is used in the city, where 90 the intense glare is objectionable, and often prohibited, the supplemental source of light is employed, the main source being cut out and the rays of light are reflected downwardly upon the road directly in advance 95 of the car, and the reflectors being small, only a sufficient amount of light will be projected to enable the driver to obtain a clear vision of the path of travel. When, however, the car is traveling in the rural districts or open country and it is desired to use the full power of the lamp the supplemental source of light is cut out and the main source cut in, and inasmuch as the rear surface of the supplemental reflector is polished to provide a reflecting surface the light rays which would otherwise be obstructed by said supplemental reflector are 100 105

thrown back to the main reflector and there reflected again so that approximately the full power of the lamp is obtained and the only obstruction which does occur will in a 5 measure eliminate the intense glare from the center of the lamp without materially impairing the search light properties thereof.

If desired both the main and supplemental lights could be employed where the utmost power is needed.

While I have shown only one form of my invention it is obvious that certain changes and modifications can be made without departing from the broad principle thereof within the scope and meaning of the appended claims.

Having thus described my invention, what I claim is:

- 20 1. In a lamp, the combination with a main unbroken reflector, of a supplemental reflector arranged within the confines of the main reflector and adjacent the edge thereof, said supplemental reflector being of less diameter than the main reflector.
- 25 2. In a lamp, the combination with a main unbroken reflector and its source of light, of a supplemental reflector and its source of light, said supplemental reflector being arranged within the confines of the main reflector, both the inner and outer surfaces 30 of said supplemental reflector being reflecting surfaces.

reflector and at an angle to the axis of said main reflector.

3. In a lamp, the combination with a main unbroken reflector and its source of light, of a supplemental reflector and its source of light, said supplemental reflector being of considerably less diameter than the main reflector, arranged within the confines thereof adjacent one edge and at an angle to the axis of said main reflector. 35

4. In a lamp, the combination with an unbroken reflector and its source of light, of a supplemental reflector and an independent source of light, said supplemental reflector being of considerably less diameter than the main reflector and arranged within the 40 confines thereof.

5. In a lamp, the combination with an unbroken reflector and its source of light, of a supplemental reflector and its source of light, said supplemental reflector being arranged within the confines of the main reflector adjacent one edge thereof and in advance of the source of light of the main reflector, both the inner and outer surfaces 45 of said supplemental reflector being reflecting surfaces. 50

In testimony whereof, I hereunto affix my signature.

WILLIAM F. PERSONS.
